UNITED STATES PATENT OFFICE.

OSCAR ZERK, OF CLEVELAND, OHIO, ASSIGNOR, BY MESNE ASSIGNMENTS, TO GEORGE W. BOWEN, OF AUBURN, NEW YORK.

THUMB-SCREW.

1,094,768.

Specification of Letters Patent. Patented Apr. 28, 1914.

Application filed April 3, 1913. Serial No. 758,553.

To all whom it may concern:

Be it known that I, OSCAR ZERK, a subject of the Emperor of Austria-Hungary, residing at Cleveland, in the county of Cuyahoga and State of Ohio, have invented a certain new and useful Improvement in Thumb-Screws, of which the following is a full, clear, and exact description, reference being had to the accompanying drawings.

10 The object of this invention is to provide a very simple and effective thumb screw, in which the head may be made by stamping from sheet metal, and the screw may be formed in any suitable manner, the head being rigidly secured on the shank of the screw.

My invention is hereinafter more fully described and its essential characteristics set out in the claims.

20 In the drawings, Figure 1 is a central side elevation partly in section of my thumb screw; Fig. 2 is a plan of the blank from which the head of the thumb screw is made; Fig. 3 is a section through a pair of dies for 25 converting the blank into a trough-shaped member, the bottom portion of the trough being shown in section in this view; Fig. 4 is a cross section through the lower die of Fig. 3 and illustrating also the trough-shaped member being stamped; Fig. 5 is a 30 perspective view of such trough-shaped member; Fig. 6 is a vertical section of the next set of dies and a section of the trough-shaped member being stamped thereby; Fig. 35 7 is a perspective view of the product of the dies shown in Fig. 6. Fig. 7 shows the head ready to be mounted on the shank of the screw.

As shown in Fig. 1, A represents the head 40 of the screw, B the screw proper, and C a piece of metal in which the screw is journaled. The screw is shown as having a collar b' below the member C and a cylindrical shank b'' extending through the member and 45 occupying a tubular portion of the head A. The finished head is substantially of the form shown in inverted position in Fig. 7. It has the two doubled together portions a , and the tubular portions a' extended at a'' 50 beyond the edges of the side portions.

The head having the form just described is made by stamping from a suitable blank, such as shown at A' in Fig. 2, being a rectangular blank, except that it has a pair of 55 projecting short wings A'' . This blank is

placed between dies shown in Fig. 3. The die here shown as the upper die has a rib D rounded at its lower edge and intermediately provided with vertical rounded bosses D'. The die E is a female correspondingly 60 formed. The blank is placed between these two, and, by reason of the coaction of the dies, is pressed into the trough-shaped form shown in Fig. 5 with the outward bosses A² on the two side portions. The trough-shaped member, as shown in Fig. 5, is then placed between the two dies F and F' and a suitable stud or mandrel G is placed between the bosses A². The pressure of the dies F and F' toward each other presses the trough-shaped wings onto each other and presses the trough-shaped bosses into semi-circular form about the mandrel G, the blank thus taking the form shown in Fig. 7. The head having the form shown in Fig. 7 is placed 70 over the shank b' of the screw and secured thereto in any suitable manner, as, for example, by the drilling of the hole through the head and shank and driving into such hole the pin H. When the head is mounted 75 on the thumb screw it has the appearance and operation of a head machined from a single bar. The line between the two sides of the metal plate of which the head is formed is emphasized in Fig. 7 for clearness 80 of illustration. In practice it is hardly noticeable and disappears altogether when the head is plated. By making the head and screw separable, the screw may be rotatably mounted in an intermediate member, as 85 shown in Fig. 1. In that case the extension a'' of the tubular portion of the head furnishes a suitable collar for taking the thrust against that side of the intermediate member, the rigid collar on the screw taking the 90 opposite thrust.

Having thus described my invention, what I claim is:

1. A thumb screw consisting of a stem portion threaded at one end, and a head or handle formed from a blank of sheet metal doubled upon itself to provide corresponding sides and a connecting portion, the latter being located substantially in alignment with the axis of the stem, and the sides embracing opposite sides of the stem, and means for rigidly connecting the head to the stem, substantially as and for the purpose described. 100

2. A thumb screw consisting of a stem 110

having a threaded portion, a head or handle formed from a blank of sheet metal and comprising corresponding sides and a connecting portion, said sides having corresponding arcuate portions forming a socket, one end of the stem being inserted in said socket and said connecting portion extending transversely across the extremity of said end, and means for connecting the head to the stem, substantially as and for the purpose specified.

3. A thumb screw comprising a stem having a threaded portion, a sheet metal head provided with corresponding sides and a connecting portion, said sides having arcuate portions intermediate their ends and the parts of one side between the arcuate portion and the ends thereof being pressed into intimate contact with the corresponding portions of the other side, and one end of the stem being inserted between the arcuate portions of the two sides, said connecting portion of the head extending transversely across the extreme end of the stem, and means for connecting the head to the stem, substantially as and for the purpose set forth.

4. A thumb screw consisting of a stem threaded at one end, and a head or handle formed from sheet metal and comprising corresponding sides and a connecting portion, the latter extending across one end of the stem, and the sides of the head ex-

tending in planes parallel to the longer axis of the stem, said head being provided with a socket for receiving the end of the stem, the walls of the socket being formed by deflected portions of the sides, substantially as and for the purpose described.

5. A thumb screw consisting of a sheet metal blank, bent into a trough-shape with arcual externally convex transverse bosses on its opposite sides, the side portions between the bosses and the ends being pressed together, the shank of a screw being mounted in the intermediate recess which is left.

6. A thumb screw consisting of a substantially rectangular blank with short wings on its opposite sides, doubled intermediately into a trough-shape with transverse arcual bosses terminating in the wings, the side portions beyond the bosses being pressed together, whereby a head is provided having a tubular central portion with projecting flat extensions, the tubular portion projecting beyond the edge of the extensions, and there being secured in such tubular portion a suitable shank of a screw.

In testimony whereof, I hereunto affix my signature in the presence of two witnesses.

OSCAR ZERK.
